DESIGN FOR A HANDBAG FRAME

Angelo J. Fleres, Hollis, Long Island, N. Y.

Application March 20, 1948, Serial No. 145,256

Term of patent 7 years

(Cl. D87—1)

To all whom it may concern:

Be it known that I, Angelo J. Fleres, a citizen of the United States, residing at Hollis, Long Island, New York city, in the county of Queens and State of New York, have invented a new, original, and ornamental Design for a Handbag Frame, of which the following is a specification, reference being had to the accompanying drawing, constituting a part thereof.

Fig. 1 is a plan view of an open handbag frame, showing my new design.

Fig. 2 is a side elevational view of the frame shown in Fig. 1.

Fig. 3 is a cross-sectional view along line 3—3 of Fig. 1 looking in the direction of the arrows, and

Fig. 4 is a bottom view of the frame shown in Fig. 1.

I claim:

The ornamental design for a handbag frame, substantially as shown.

ANGELO J. FLERES.
